FLAT SHEET LATEX ARTICLE

Abraham N. Spánel, Rochester, N. Y.

Application August 16, 1934, Serial No. 740,141

12 Claims. (Cl. 2—49)

This invention relates to flat sheet latex articles.

This application is a continuation in part of applicant's co-pending applications Serial Number 684,549, filed August 10, 1933 now abandoned, and Serial Number 696,037, filed October 31, 1933 Patent No. 2,015,632, dated September 24, 1935.

The main purpose of the invention is to provide sheet latex articles, of which some or all of the edges thereof are strengthened by a reinforcement integral with the article.

A further purpose of the invention resides in the provision of forms on which flat latex articles suitably reinforced against tearing can be made by depositing latex thereon, such as by dipping the form into a bath of latex.

The various features of the invention will appear from the detailed description and claims when taken with the drawings in which Fig. 1 is a plan view of a reinforced latex sheet; Fig. 2 is an enlarged fragmentary view thereof, indicating the character of reinforcement at the margin of the sheet; Figs. 3 and 4 are sectional views of the sheet taken respectively on the lines 3—3 and 4—4 of Fig. 1, indicating the character of the two different types of reinforcement of the edge of the sheet; Fig. 5 is a plan view of a baby's bib or apron made of latex and Figs. 6 and 7 are sectional views thereof taken respectively on the lines 6—6 and 7—7 of Fig. 5 indicating the character of reinforcement of the side edges and bottom edge of the article; Fig. 8 is a plan view of a latex cape; Figs. 9 and 10 are fragmentary sectional views thereof taken respectively on the lines 9—9 and 10—10 of Fig. 8, illustrating the character of reinforcement of the margin of this cape; Fig. 11 is a front elevation of a form on which a latex sheet can be made according to the present invention; Fig. 12 is a cross sectional view of this form taken on the line 12—12 of Fig. 11 and also indicating a section of latex sheeting removed from the form; Fig. 13 is a front elevation of a modified type of form on which latex sheeting can also be made; Fig. 14 is a side elevation of this form; Fig. 15 is a cross sectional view thereof, taken on line 15—15 of Fig. 13; Fig. 16 is a fragment of a latex sheet which can be made on the form of Fig. 13; Fig. 17 is a vertical section taken through the sheeting along a line intersecting the two corner openings therein; and Fig. 18 is a cross sectional view taken through the latex sheeting; Fig. 19 is a front elevation of a form on which a shower bath curtain of latex can be made; Fig. 20 is a vertical

section of this form taken substantially on the line 20—20 of Fig. 19; Fig. 21 is a vertical section with parts thereof broken away of a shower bath curtain which can be made on this form; Fig. 22 is a front elevation of a form on which a baby's bib or an apron of latex can be made; Fig. 23 is a side elevation of this form; Fig. 24 is a section taken on the line 24—24 of Fig. 22; Fig. 25 is a fragmentary vertical section of the latex bib or apron that can be made on this form; and Fig. 26 is a fragmentary horizontal sectional view taken through the neck opening of the bib or apron; Fig. 27 is a fragmentary plan view of a flexible form or belt on which a continuous latex strip with reinforced margins can be made; Fig. 15 28 is a cross sectional view taken through this belt on line 28—28 of Fig. 27, also indicating in cross section two endless latex strips removed from the form; Fig. 29 is a front elevation of a form on which two latex capes can be made simultaneously; Fig. 30 is a side elevation of this form with sectional fragments of the cape removed therefrom to indicate the character of reinforcement of the various exposed edges of the cape; and Fig. 31 is a cross sectional view of this 25 form taken on the line 31—31 of Fig. 29.

Referring especially to Figs. 1 to 4 inclusive, 5 designates a sheet of latex having its margins 6, 7 and 8 reinforced as indicated at 9 (Fig. 3) by an accretion of latex integral with the sheet 30 and terminating in a torn or feathered edge 10. The fourth margin 11 of the sheet as indicated at 12 in Fig. 4 is reinforced by an accretion of latex which is somewhat similar in cross section to substantially, one half of the vertical section 35 of a tear drop. The free edge of this reinforcement indicated at 13 terminates in a torn or feather edge. It should be noted that this sheet has two types of reinforcement, such as 9 and 12, which merge one into the other, as indicated 40 at 14 in Fig. 2. The sheet 5 may be provided with corner openings 15 therein and if such openings are provided in the sheet, the material at the margin of each opening will be reinforced by an accretion of latex as best indicated in Fig. 6. 45

Figs. 5, 6 and 7 disclose a latex bib or apron 16 made in accordance with the present invention. The lower portion of this bib may be generally rectangular, while its upper portion narrows down to two curved tabs 17 defining a neck opening. The ends of these tabs are provided with holes 20 to receive a button or other fastening means (not shown) which serve to hold the tabs together around the neck of the wearer. All the margins of this bib are reinforced by an accre- 55

tion of latex 18 integral with the bib and terminating in a feather or torn edge 19. Similarly, the bib at the holes 20 therein is reinforced by an accretion of latex 21 integral therewith and 5 terminating in a feather or torn edge 22.

Figs. 8, 9 and 10 disclose one style of latex cape 23 which is made in accordance with the present invention. This cape, which is made of one piece of latex has a collar, 24 and straps or ties 25 serving to fasten the cape around the neck of the wearer. This cape also has shoulder portions 26 connected with the neck portion thereof, which shoulder portions flare outwardly to the bottom portion 27 of the cape. As herein illustrated, the cape is provided with openings 28 to receive buttons or other fastening means. All margins of the cape, including those of the collar, 24 the straps 25, the shoulder portions 26 and the other portions thereof are reinforced by a 10 ridge of latex thereat, which ridge is preferably continuous. The reinforcing ridge of all margins of the cape, except that at the bottom margin 27 is of the character indicated at 29 (Fig. 9), terminating in a torn or feather edge 30. However, 15 the reinforcing ridge 31 at the margin of the lower portion 27 of the cape, is somewhat similar in cross section to substantially one half of the vertical section of a drop while the free edge of this ridge terminates in a torn or feather edge 32 (Fig. 10). The buttonholes 28 in the cape are 20 each reinforced by a ridge or an accretion 33 integral with the layer of the cape which ridge may terminate in a torn or feather edge 34 or in a cut edge as desired.

35 One type of latex sheet can be made on the form shown in Figs. 11 and 12. This form comprises a substantially rigid plate having panels 35 and 36, which panels are bounded on three of their sides by the raised border 37. This border is provided with abrupt edges 38 and 39, adjacent to each of its junctions 40 and 41 with the respective panels. The bottom of this form as illustrated in Fig. 11, is not provided with a raised border, but instead terminates in an abrupt 45 edge 42 for each panel.

In the making of latex sheets on this form, liquid latex is deposited thereon, preferably by dipping the form while suspended from the support 43, one or more times into a liquid latex bath with 50 a drying interval between each dip until a layer of the desired thickness is deposited on the form. During the dipping operations the latex will tend to flow away from the abrupt edges 38, 39 and 42 to define lines of weakness thereat in the deposited layer but will tend to accrete by surface tension at the junctions 40 and 41 and will accrete in substantially the shape of one half of a drop above the edges 42. After the deposited layer is 55 properly dried and cured the portion thereof on the border 37 is stripped or torn away as far as the lines of weakness in the layer at the abrupt edges 38 and 39. The portion 44 of the layer on each panel can then be stripped therefrom and can be torn or parted from the remainder of the layer at the lines of weakness defined by the edges 42. Three of the margins of this sheet will be reinforced by an accumulation 45 (Fig. 12) of latex integral with the sheet and having a torn or feather edge 46. The fourth margin, 60 however, will be reinforced by a ridge of latex integral therewith, which ridge in cross section is somewhat similar to that of substantially one half of the vertical section of a drop. The free edge of this reinforcement will be in the form 75

of a torn or feather edge as will appear herein-after.

A form similar to that last described but adapted to making latex sheets with rounded corners, is illustrated in Figs. 13, 14 and 15. This form is likewise provided with two panels 48 and 49 partially bounded by a raised border 50 which is provided with rounded corners at its upper portion. The border 50 is provided with abrupt edges 51 and 52 and is connected with the panels 5 at the junctions 53 and 54. This border is also provided with supports 55 by which the form 10 can be suspended while it is being coated or dipped. Adjacent to each of the corners of the panels 48 and 49 there are provided bosses 56 15 which rise abruptly from the surface of the panel and terminate in abrupt edges 57. The lower edge and lower corners of the panel are not bounded by the border 51 but instead terminate in an abrupt edge 58. It should be noted that 20 the lower ends of the border 50 extend to a point below the center of curvature of the rounded lower corners of the panel.

In making sheeting on this form the form is 25 coated or dipped as previously described, as a result of which the latex sheet 5, which is shown in Figs. 1 to 4 inclusive, will be formed. The border 50 generates a reinforcement 9, at three 30 of the margins of the sheet, which reinforcement terminates in a torn or feather edge 10. However, the abrupt lower edge 58 of the form defines the reinforcement 12 which terminates in a torn or feather edge 13. It will be understood that the reinforcement 12 merges with the reinforcement 9 as indicated at 14 in Figs. 2 and 16. The 35 bosses 56 on the panel generate holes 15 in the sheet, the material at the margin of each hole being reinforced as indicated at 60, which reinforcement terminates in a torn or feather edge 61.

When the invention is utilized in making a 40 shower bath curtain 63, the form shown in Figs. 19 and 20 is employed. This form differs from that just described in that its dimensions are different and a single row of bosses 62 is provided along the upper margin of the panels. 45

In making the bib or apron shown in Fig. 5, a form illustrated in Figs. 22, 23, and 24 is provided. This form which is adapted for the making of a bib or apron on each side thereof simultaneously, is provided with two depressed panels 50 64 and 65, which panels are bounded by a continuous border 66. This border at its upper portion converges toward the top where it connects with a circular boss 67. This boss which is of such size as to define a neck opening, also serves 55 to define neck bands or straps 17 (Fig. 5). The border 66, as well as the boss 67, rise abruptly from the junctions 68 with the panel, while the border and the bosses terminate in abrupt edges 69. Those portions of the form where it is desired to provide holes for buttons or other fasteners in the resulting bib, are provided with bosses 70 projecting abruptly from the form and terminating in abrupt edges. 60

A continuous latex strip 84 (Fig. 28) with reinforced margins 85 can be made in accordance with this invention. In the making of such a latex strip an endless flexible belt (Fig. 27) such as 80 is provided, a fragment only of which is herein disclosed. This belt as herein shown is provided at 70 each edge with a raised border 81, which projects abruptly from the face of the belt and terminates in abrupt edges 82. It will be noted that the belt is so shaped that a continuous strip may be formed on each surface thereof. While the belt 75

can be supported and driven in any convenient manner, it preferably is provided with fins 83 which pass between driven rolls so that a portion of the belt can be dipped into a latex bath and then moved to a drying and curing position. A continuous sheet 84 thus formed on each surface of the belt has its margin reinforced by a ridge 85 which terminates in a torn or cut edge 86.

The cape illustrated in Fig. 8 can be made on a form 90 illustrated in Figs. 29, 30, and 31. This form which is adapted to making simultaneously a cape on each surface thereof, is provided with the panels 91 and 92. These panels with the exception of the lower portion thereof are bounded by a border 93 which rises abruptly from its junction with the panel and which terminates in an abrupt edge 94. The lower corners and lower portions of the panels, however, are not provided with a border, but instead terminate in abrupt edges 95 with rounded corners identical with those shown in Figs. 13 and 19. The panels are provided with raised bosses 96 on those portions thereof where it is desired to generate an opening in the resulting cape. It will be understood that the border 93 and its related panel generates the reinforcement 29 for the margin of the cape, which reinforcement terminates in a torn or feather edge 30. However, the abrupt edge 95 of the form generates the type of reinforcement indicated at 31 which reinforcement terminates in a torn or feather edge 32. The bosses 96, however, generate the holes 28 in the cape, which holes are reinforced as indicated at 33 with the reinforcement terminating in a torn or feather edge 34.

In making latex capes on this form, a layer of latex is deposited thereon such as by dipping the form into a latex bath in the manner set forth above. Thereafter the excess portion of the latex layer as far as the abrupt edges 94 and 95 is separated from the resulting capes by cutting, stamping, clicking or tearing. The portions of the layer covering the faces of the bosses 96 are likewise removed by cutting or tearing to provide the buttonholes 28 in the capes.

The term "accretion" as herein used means a reinforcement for a margin of the garment, which reinforcement is built up naturally by a gradual increase or external addition of the liquid latex due to the cohesion thereof and without the use of mechanical pressure as in the case of molding rubber.

While several embodiments of the invention have been disclosed, it will be understood that this invention is capable of still further modifications and that this disclosure is intended to cover any variations, uses or adaptations of the invention falling within the scope of the appended claims.

60 What I claim is:

1. A seamless deposited latex sheet-like article having its entire margin reinforced by an accretion of latex integral therewith.

2. A seamless deposited latex sheet having its entire margin reinforced by a continuous accretion of latex integral therewith.

3. A seamless deposited latex sheet having its entire margin reinforced by an accretion of latex integral therewith, said sheet having button holes or the like provided therein, the margin of said sheet at each hole being reinforced by an accretion of latex.

4. A seamless deposited latex sheet-like article having its entire margin reinforced by an accretion of latex integral therewith, with the edge of a portion of said accretion terminating in the plane of the article.

5. A seamless deposited latex sheet-like article having its entire margin reinforced by an accretion of latex integral therewith with the edge of a portion of said accretion projecting generally outside of the plane of the article.

6. A seamless deposited latex sheet-like article having its entire margin reinforced by accretions of latex integral therewith, the edge of one of said marginal accretions terminating in the plane of the article and the edge of another of said marginal accretions projecting generally outside of the plane of the article.

7. A seamless deposited latex sheet, the entire margin of said sheet being reinforced by an accretion of latex integral therewith, said accretion having parts of materially different cross section, one of said parts having a cross section which is generally semi-pear shaped.

8. A seamless deposited latex sheet having rounded corners, the entire margin of said sheet being reinforced by an accretion of latex integral therewith, said accretion having parts of materially different cross section, merging one into the other, one of said parts being generally semi-pear shaped in cross section.

9. A seamless deposited latex bib having at its upper portion integral straps to define a neck opening, each strap having a hole therein to receive fastening means, the entire margin of said bib being provided with an accretion of latex integral therewith.

10. A seamless deposited latex cape including a body portion and a collar integral therewith, the entire margin of said cape having a reinforcing accretion of latex integral therewith.

11. A seamless deposited latex cape including a body portion and a collar integral therewith, straps integral with said cape and connected thereto between said collar and said body portion, the entire margin of said cape having a reinforcing accretion of latex integral therewith.

12. A seamless deposited latex sheet having rounded corners, the entire margin of said sheet being reinforced by an accreted ridge of latex integral therewith, the accreted ridge at one edge and the adjacent rounded corners of said sheet being generally semi-pear shaped in cross-section.

ABRAHAM N. SPÁNEL.
